UNITED STATES PATENT OFFICE.

JOSEPF VASS, OF SHARPSVILLE, PENNSYLVANIA.

RAIL-JOINT.

1,388,445.

Specification of Letters Patent. Patented Aug. 23, 1921.

Application filed February 18, 1921. Serial No. 445,940.

To all whom it may concern:

Be it known that I, JOSEPF Vass, citizen of Hungary, and resident of Sharpsville, in the county of Mercer and State of Pennsylvania, have invented certain new and useful Improvements in Rail-Joints, of which the following is a specification.

This invention relates to rail joints for railway tracks, and it has for an object to provide a novel and improved form of rail joint which will permit of creeping of the individual rails and avoid danger of the same buckling upon increase of temperature.

More specifically speaking the invention has for an object to provide a rail as above set forth which maintains the continuity of the tread at the joints and also holds the rail sections or lengths properly against relative displacement either laterally or vertically, and also serves to prevent any undesirable longitudinal movement of the rail ends away from one another.

For further comprehension of the invention, and of the objects and advantages thereof, reference will be had to the following description and accompanying drawings, and to the appended claims in which the various novel features of the invention are more particularly set forth.

Figure 1 of the drawings is a perspective view showing a pair of rail ends joined according to the invention.

Fig. 2 is a side elevation of the separate rail ends.

Fig. 3 is a bottom plan view of the rail ends joined as in Fig. 1.

Fig. 4 is a transverse section taken at the point indicated by the line 4-4 in Fig. 1. In the drawings the numerals 10, 11 indicate the rail ends generally. In constructing my improved rail joint the tread 10' of the rail 10 has cut vertically therethrough a T-slot 12, the web 10^a being cut out under this T-slot as at 13. The base flange 10^b of the rail 10 is formed with a pair of elongated apertures 14 which register with this cut out part 13.

The rail 11 has the tread 11' thereof cut out on opposite sides as at 16 flush with the web 11^a a short distance from the end of the rail, while the portion of the tread between this cut out 16 and the extreme end of the rail is diminished in width to form a pair of

projections 17, thus forming a T-head which is adapted to engage in the T-slot 12.

The base flange 11^b of the rail 11 is cut away as at 18 from a point in vertical alignment with the inner wall of the cut out 16 in the tread 11' to the end of the rail, the projecting portion 19 of the base flange 10^b being accommodated in this cut out. Projecting downwardly from the web 11^a into the cut out 18 are a pair of integral studs 20 which are adapted to engage in the elongated apertures 14.

Formed on each side of the web 10^a of rail 10 are a pair of angular guide flanges 22 which may extend along the rail from the end thereof to a point slightly beyond the inner wall of the T-slot 12. Each of these pairs of guide flanges 22 forms, in cooperation with the web of the rail, a T-guide. Each of these T-guides is adapted to have engaged therein a bar 24, of which there is one on each side of the rail webs 11^a, these bars being secured together by a bolt 25 on which is screwed a nut 26, this bolt passing through suitable registering apertures in the bars 24 and the web 11^a.

To provide for relative longitudinal movement of the two rails 10 and 11 the projections 17 are of less dimension, longitudinally of the rail, than the head of the T-slot 12, while the distance from said head of the T-slot 12 to the end of the rail 10 is less than the longitudinal dimension of the cut out 16. The studs 20, being of circular cross section, are permitted longitudinal movement in the apertures 14.

In assembling the rail joint the rail end 11 is projected over the rail end 10 until the projections 17 register with the head of the T-slot 12 in which position the studs 20 on rail 11 will also register with the apertures 14 in rail 10. Rail 11 is then dropped into position, the projections 17 engaging in the head of the T-slot 12 while the top wall of the cut out part 18 of the rail 11 rests on the projecting end 19 of the base flange 10^b. The bars 24 are then slid into the retaining guides formed by the angular flanges 22 and secured in place by the bolt 25.

With the joint as thus constructed it will be noted that there is no break in the continuity of tread of the railroad tracks while at the same time provision is made for limited individual creeping of the rails, while rela-

tive vertical and transverse displacement of the rail ends is prevented respectively by the bars 24 and guide flanges 22, and the projecting end of rail 11 engaging in the T-slot 12.

Having thus described my invention what I claim as new and desire to protect by Letters Patent of the United States is as follows:

10. 1. In a rail joint, a pair of rail ends one of which has the tread portion presenting a vertically extending T-slot, the other of said rail ends having the tread thereof cut out on opposite sides flush with the web at a distance from the end thereof, the extreme end of said tread being of diminished width to form a pair of projections presenting a T-head engaging in said slot, and means locking said rail ends against relative vertical displacement, said means comprising a pair of bars detachably secured to the web of one rail end and retainer guides on the other rail end in which said bars engage slidably.
25. 2. In a rail joint, a pair of rail ends one of which has the tread portion presenting a vertically extending T-slot, and having the web thereof cut out in vertical alinement with the inner end of said T-slot leaving a projecting base flange portion, the other of said rail ends having the tread thereof cut out on opposite sides flush with the web at a distance from the end thereof, and having the base flange cut out in correspondence to the said projecting base flange element.
30. 3. In a rail joint, a pair of rail ends one of which has the tread portion presenting a vertically extending T-slot, and having the web thereof cut out in vertical alinement with the inner end of said T-slot leaving a projecting base flange portion, the other of said rail ends having the tread thereof cut

out on opposite sides flush with the web at a distance from the end thereof, and having the base flange cut out in correspondence to the said projecting base flange element, and means locking said rail ends against relative vertical displacement.

4. In a rail joint, a pair of rail ends one of which has the tread portion presenting a vertically extending T-slot, and having the web thereof cut out in vertical alinement with the inner end of said T-slot leaving a projecting base flange portion, the other of said rail ends having the tread thereof cut out on opposite sides flush with the web at a distance from the end thereof, and having the base flange cut out in correspondence to the said projecting base flange element, and means locking said rail ends against relative vertical displacement, said means comprising a pair of retainer guides formed on the first mentioned rail end, and a pair of bars detachably secured to the other rail end and engaging in said retainer guides.

5. In a rail joint, a pair of rail ends one of which has the tread portion presenting a vertically extending T-slot, and having the web thereof cut out in vertical alinement with the inner end of said T-slot leaving a projecting base flange portion, the other of said rail ends having the tread thereof cut out on opposite sides flush with the web at a distance from the end thereof, and having the base flange cut out in correspondence to the said projecting base flange element, said last rail end having studs projecting downward into the last mentioned cut out and adapted to engage in apertures in the said projecting base flange portion.

Signed at Sharpsville, in the county of Mercer and State of Pennsylvania, this 16th day of February, A. D. 1921.

JOSEPF VASS.
